(57) **CLAIM**

The ornamental design for a handheld analyzer, substantially as shown and described.

DESCRIPTION

FIG. 1 is a left elevation view of an embodiment of the handheld analyzer;

FIG. 2 is a left elevation view of the embodiment of the handheld analyzer, wherein the screen is in the tilted position;

FIG. 3 is a front, left perspective view of the embodiment of the handheld analyzer;

FIG. 4 is a right elevation view of the embodiment of the handheld analyzer;

FIG. 5 is a front elevation view of the embodiment of the handheld analyzer, wherein the screen is in the tilted position;

FIG. 6 is a back elevation view of the embodiment of the handheld analyzer;

FIG. 7 is a back, left perspective view of the embodiment of the handheld analyzer;

FIG. 8 is a back, left perspective view of the embodiment of the handheld analyzer, wherein the screen is in the tilted position;

FIG. 9 is a top plan view of the embodiment of the handheld analyzer, wherein the screen is in the tilted position; and, FIG. 10 is a bottom plan view of the embodiment of the handheld analyzer.

The broken lines in the figures form no part of the claimed design.

1 Claim, 10 Drawing Sheets
